(57) **CLAIM**

The ornamental design for a correction tape dispenser, as shown and described.

DESCRIPTION

FIG. 1 is a front perspective view of a correction tape dispenser according to an embodiment of the invention;
FIG. 2 is a front plan view of a correction tape dispenser according to an embodiment of the invention;
FIG. 3 is a back plan view of a correction tape dispenser according to an embodiment of the invention;
FIG. 4 is a right plan view of a correction tape dispenser according to an embodiment of the invention;
FIG. 5 is a left plan view of a correction tape dispenser according to an embodiment of the invention;
FIG. 6 is a top plan view of a correction tape dispenser according to an embodiment of the invention;
FIG. 7 is a bottom plan view of a correction tape dispenser according to an embodiment of the invention; and,
FIG. 8 is a front perspective view of a correction tape dispenser having correction tape thereon according to an embodiment of the invention.
